CLAIM

The ornamental design for an organizer rack for storage of firewood, kindling, newspaper and fireplace tools, as shown.

DESCRIPTION

FIG. 1 is a perspective view of an organizer rack for storage of firewood, kindling, newspaper and fireplace tools showing our new design;

FIG. 2 is a side elevational view thereof;

FIG. 3 is a front elevational view thereof;

FIG. 4 is a top plan view thereof; and,

FIG. 5 is a rear elevational view thereof.
